UNITED STATES PATENT OFFICE.

SHORTRIDGE HARDESTY, OF LARCHMONT, AND WILLIAM G. WILLIAMS, OF FLUSHING, NEW YORK, ASSIGNORS TO WADDELL & HARDESTY, OF NEW YORK, N. Y., A CO-PARTNERSHIP COMPRISING JOHN A. L. WADDELL AND SHORTRIDGE HARDESTY.

LIFT BRIDGE.

Application filed February 17, 1927. Serial No. 168,907.

The invention aims to provide an improved combination of devices by which power lines are carried to a motor on the moving span and by which the changing 5 stress of the usual counterweight cables is very simply compensated.

The accompanying drawings illustrate an embodiment of the invention.

Fig. 1 is a side elevation of a vertical lift bridge, partly broken away; Fig. 1^a being a detail thereof;

Fig. 2 is a side elevation of part of the apparatus on an enlarged scale, the view being taken on the line 2—2 of Fig. 1;

Fig. 3 is a side elevation of parts shown in Fig. 2.

The movable span of the bridge is indicated generally at 1 and the fixed towers at 2. The trusses of the right-hand tower are broken away at the top to show the parts behind them more clearly. The weight of the lift span is counterbalanced by weights 3 suspended from cables 4 which pass upward over sheaves 5 at the tops of the towers. 25 They are connected to the counterweights through equalizers 6. Their opposite ends extend downward from the sheaves and are connected to cross-girders 7 on the ends of the moving span. The span is lifted and 30 hauled down by means of cables 8 attached to the bottoms and tops of the towers, with their bight passing over guide pulleys 9 on the ends of the span and finally over drums 10 at the center which are driven by suitable 35 motors located in the machinery house 11 mounted on the top of the span. At the ends of the span are guide shoes 12 which engage suitable vertical guides on the faces of the towers. On the underside at each end of 40 the span are bearing shoes 13 and 14, the former fixed on the pier 15 and the latter being a rocker pivotally supported on the span so as to allow for longitudinal movement of 45 expansion.

Mounted on top of the machinery house is a rocker 16 in the form of a structural steel bent illustrated in detail in Figs. 2 and 50 3, supported on hinges 17 at its lower end and carrying at its upper end circular drums or guides 18. These are provided with spiral 55 grooves shown in Fig. 2 around which are wrapped ropes 19, fixed at one end to a tower and carrying at their opposite ends counter- 60 weights 20 below guide sheaves 21 fixed on

the tower. As shown in Fig. 1 the left-hand 55 ends of the ropes 19 pass through saddles 22 with curved bearing faces and are fastened to supporting blocks 23 on top of the tower. From the saddles 22 the ropes 19 lead downward and wrap around the drums 18 to 60 which they are clamped at one point and are continued around the drum and up to the guide sheave 21.

The power line or electric conductor 24 is supported by cleats or similar devices 25 arranged on the left-hand portion of the ropes 19, and passes at its upper end over suitable guides and down along the outside face of the tower as indicated. Before reaching the central drum 18 the cable 24 is loosely 70 carried down to the machinery house 11 and into the same.

The lift span, counterweights, etc. are shown in full lines in the closed position of the bridge and in dotted lines in the open position. During the operation of the span, ropes 19 are maintained taut by the counterweight 20 which alternately falls and rises, and the bent 16 rocks about its pivot 17 causing the center of guides 18 to move through 80 the path indicated by the circular dotted line of Fig. 1. Power lines 24, supported by ropes 19, meanwhile maintain their connection to the span with only slight changes of angle at any one point and with a minimum 85 of slack in any of their parts.

The vertical component of the pull of the ropes 19 on the span, acting through bent 16, varies from an upward to a downward direction as the span rises and passes through a neutral position of no vertical component when the span is in the half open position. We therefore can construct counterweight 90 20 of such weight that these vertical components will balance or compensate for the unbalanced weight of the main counterweight ropes as they pass from one side to the other of the sheaves 5. The desired compensating effect may be obtained also by varying the positions and proportions of the 95 several parts of the apparatus by which the electrical conductor is carried. And in any case the invention may be advantageously applied to a partial counterbalancing of the variation caused by the weight of the main 100 counterweight cables, though preferably the parts are designed to secure substantially 105 complete counterbalancing.

By means of our device therefore we are enabled to dispense with the chains, heavy ropes and other devices commonly used heretofore to balance the variable portion of the 5 main counterweight ropes as well as to maintain direct connection of the power lines to the span, without the disadvantages met with in the use of great hanging loops or trolley or sliding contacts, liable to be 10 damaged by high winds and ice or snow.

Figs. 2 and 3 show enlarged details of the rocker bent 16 in which guide castings 18 are shown in the shape of drums with a single spiral groove. These drums are keyed 15 to pins or trunnions which are rigidly attached to rocker bent 16 by connections 28. If desired, the drums 18 may be directly riveted or bolted to bents 16. Again, instead of a complete drum, two semi-circular 20 segments (similar to saddles 22) with straight grooves may be used placed one below the other with their grooves tangent at their center points. In either case the ropes are rigidly clamped to the drum or segments at some point of permanent contact with it as by clamp 30 shown in Fig. 3. And various other forms of connection may 25 be used.

Saddles 22 on the tower may be dispensed 30 with if swiveled end connections are provided for the attachment of ropes 19 to that tower. In the same way ropes 19 may be made in two parts and pivoted end connections to the rocker bent 16 be substituted 35 for drums 18.

In a co-pending application of Hardesty 40 there is described an arrangement for balancing the variable parts of the main counterweight cables independently of the scheme for leading the electrical conductors to the motor. In a separate application of Williams, co-pending herewith, there is described 45 a scheme for leading the electrical cables to the motor. These separate inventions are not claimed herein, the present application being directed to the arrangement by which both purposes are accomplished in a single structure or combination of parts.

Various modifications may be made with-

out departing from the invention as defined 50 in the following claims.

What we claims is:

1. The combination with a lift span of a motor carried thereon, a conductor leading from a fixed support to the motor and means 55 for taking up the slack of the conductor as the span moves and at the same time counterbalancing loads which vary as the span rises.

2. In combination with a lift span carrying a motor, a swinging member carried by the span, a conductor leading from a fixed point to the free end of said swinging member and thence to the motor and means attached to the swinging member for swinging 60 the same to maintain the conductor taut and at the same time to counterbalance loads on the span which vary as it rises.

3. The combination with a movable span carrying a motor of a swinging member 70 carried by said span, a conductor leading from a fixed point to the free end of said swinging member and thence to the motor, a flexible connection leading from the swinging member to a fixed point of support 75 at the opposite end of the span from that which carries the conductor and means for taking up the slack of said flexible connection and conductor as the span rises and for at the same time counterbalancing loads on the span which vary as it rises.

4. A vertical lift bridge span carrying a motor, a swinging member attached thereto, 80 fixed towers at the ends of the span, counterweights for the span comprising cables leading to overhead pulleys with weights on 90 their free ends, a cable leading to the swinging member from one tower and from the swinging member over a support on the other tower and carrying a counterweight and a conductor leading from one of the 95 towers to the motor and having its intermediate portion supported by a part of the cable leading to the swinging member.

In witness whereof, we have hereunto signed our names.

SHORTRIDGE HARDESTY.
WILLIAM G. WILLIAMS.
